(57) **CLAIM**

The ornamental design for a camera, as shown and described.

DESCRIPTION

FIG. 1 is a front, right, and top perspective view of a camera embodying the new design;

FIG. 2 is a back, left, and bottom perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a front, right, and top perspective view thereof shown with a lens cap.

The broken lines in the figures are shown for the purpose of illustrating portions of the camera, optional accessories, and/or environmental matter and form no part of the claimed design. The dash-dash broken lines showing an optional lens cap in FIG. 9 depict environmental subject matter and form no part of the claimed design. All other dash-dash broken lines shown in the drawings depict portions of the camera that form no part of the claimed design. The dot-dash broken lines shown in the drawings depict boundaries of the claim and form no part of the claimed design.
